UNITED STATES PATENT OFFICE.

EUGÈNE PETIT, OF PARIS, FRANCE, ASSIGNOR TO ALEXANDER SMITH & SONS CARPET COMPANY, OF YONKERS, NEW YORK.

DESIGN FOR A CARPET.

SPECIFICATION forming part of Design No. 14,103, dated July 17, 1883.

Application filed June 5, 1883. Term of patent 3½ years.

To all whom it may concern:

Be it known that I, EUGÈNE PETIT, of Paris, in the Republic of France, have invented a new and original Design for Carpets, of which the following is a specification.

The accompanying photograph illustrates my new design for carpets.

This invention relates to a new design for carpets, oil-cloths, and analogous fabrics; and it consists of the new ornamentation of parts hereinafter more fully pointed out.

A bouquet, A, which is represented in the lower left-hand corner of the accompanying photograph, is repeated also on the right above the middle of the photograph, and another repetition of it started in the upper left-hand cor-

ner of the photograph, it appearing thus that the carpet is composed of the bouquets A, that are all of the same design. Around the outlines of the leaves of each bouquet are drawn fainter shades a, which surround the space b, that is left practically vacant between the three bouquets A A A, when grouped as shown in the photograph. 20

I claim—

The design for carpets, consisting of the figures A A A, having shaded outline a and forming space b, substantially as shown.

EUGÈNE PETIT.
